Hawson & Hawson

UNITED STATES PATENT OFFICE.

CHARLES H. CASPAR, OF PHILADELPHIA, PENNSYLVANIA.

ORDNANCE.

1,310,058.

Specification of Letters Patent.

Patented July 15, 1919.

Application filed March 28, 1918. Serial No. 225,306.

To all whom it may concern:

Be it known that I, CHARLES H. CASPAR, a citizen of the United States, residing in Philadelphia, Pennsylvania, have invented 5 certain Improvements in Ordnance, of which the following is a specification.

My invention relates to ordnance, and the object of my invention is to increase the effective range of artillery, particularly heavy 10 guns.

My invention comprises means whereby an increased amount of sustained pressure from a charge of powder or other explosive may be provided, with substantially no limitation 15 in the magnitude of the explosive charge, and

These and other features of my invention are more fully described hereinafter, reference being had to the accompanying drawings, in which:

Figures 1 and 2, are, respectively, a longitudinal section and a cross section of sufficient of a gun barrel and its breech to illustrate my invention, and

Figs. 3 and 4, are similar views illustrating a modified construction within the scope of my invention.

Ordnance as usually constructed comprises a barrel having a bore of substantially uniform internal diameter throughout, the breech portion of which bore receives a charge of powder or other explosive set behind a projectile which is driven from the gun by the pressure exerted by the 35 exploding charge.

Under ordinary circumstances a gun of this type presents the smallest possible space for the charge of explosive and the shortest time of sustained pressure, which can 40 only occupy the bore between the breech block and the moving projectile. The muzzle velocity of a projectile discharged from a gun of this type is such that up to the present time their range has been approximately 45 not more than twenty-six miles.

Ordnance experts agree that if the time of sustained pressure within the bore of the gun or the magnitude of the explosive charge could be increased, greater flight 50 of the projectile would be secured. Increase of the time of sustained pressure within the bore of the gun and provision for increase in the magnitude of the explosive charge is the object of my invention, and 55 in order to provide for such conditions, the breech 1 of the gun is provided with a plu-

rality of chambers 2 for the reception of explosive charges; each chamber having a gas passage 3 communicating with the central bore 4 containing the projectile 5, so 60 that the combined force of the pressure developed by the exploding charges can be directed to such bore behind the projectile, thereby materially increasing the time of sustained pressure which, combined with 65 the increase in the magnitude of the explosive charge, effects such increased muzzle velocity of the projectile as to insure a range of substantially any distance desired. 70

In Figs. 1 and 2, I have shown a gun having four chambers for the reception of powder or other explosive charges surrounding the central bore or barrel containing the projectile; such chambers communicating 75 at suitable points with the central bore to insure the passage of the pressure to the same behind the projectile.

In Figs. 3 and 4, a similar construction is illustrated, but in this arrangement the 80 wall 1^a of the breech containing the chambers 2^a for the extra powder charges is in the form of a cylinder, instead of the independent semi-cylindrical portions each containing a chamber, as in the structure shown 85 in Figs. 1 and 2.

I claim:

1. Ordnance comprising a barrel having a bore for receiving a projectile and an enlarged breech, a plurality of explosive-charge-receiving chambers formed within said enlarged breech, and gas passages connecting said chambers with the bore of said barrel behind the projectile whereby the force developed in said chambers is directed 95 against the rear of the projectile to drive it from the barrel of the gun.

2. Ordnance comprising a barrel having a bore for receiving a projectile and an enlarged breech in which the rear end of said 100 bore is centrally disposed, a plurality of explosive-charge-receiving chambers formed within said enlarged breech, and gas passages disposed at equidistant points and connecting said chambers with the bore of 105 the barrel behind the projectile.

3. Ordnance comprising a barrel having a bore for receiving a projectile and an enlarged breech in which the rear end of said bore is centrally disposed, a plurality of 110 explosive-charge-receiving chambers paralleling said bore and formed within said en-

larged breech, and gas passages disposed at equidistant points and connecting said chambers with the bore of the barrel behind the projectile.

5. Ordnance comprising a barrel having a bore for receiving a projectile and an enlarged breech, a plurality of explosive-charge-receiving chambers formed within

said enlarged breech, and gas passages connecting the rear ends of said chambers with the bore of said barrel behind the projectile whereby the force developed in said chambers is directed against the rear of the projectile to drive it from the barrel of the gun.

CHARLES H. CASPAR.
